UNITED STATES PATENT OFFICE

2,429,106

CONSTRUCTION OF INTERNAL-
COMBUSTION ENGINES

Edward Philip Paxman, Colchester, England

Application October 4, 1943, Serial No. 504,920
In Great Britain July 14, 1942

6 Claims. (Cl. 123—55)

1

This invention relates to internal combustion engines and has particular reference to the mounting and housing of a cam shaft and its associated parts. Hitherto it has been the practice to dispose the cam shaft in an extension of the crank case or cylinder block which entailed highly skilled workmanship in assembly owing to the involved machining operations and the necessity for accurately aligning a large number of co-operating parts and the object of the present invention is to simplify the general construction of the engine, expedite assembly and render the cam shaft and parts operating in conjunction therewith more easily accessible than in former constructions.

According to the present invention the cam shaft instead of being housed within an extension of the crank case is mounted in a cam box formed as a separate component and adapted, when the cam shaft, cam rockers and their associated parts have been operatively assembled to be placed in position as a unit adjacent the cylinders whose valves are controlled by the cam shaft.

According to the preferred form of the invention a cam shaft mounting for an internal combustion engine comprises a cam box formed as a separate component and providing bearings for a cam shaft and a rocker shaft both extending through the length of said cam box which is provided with a cover adapted to support a fuel pump and other components in such manner that the complete assembly can be placed in position upon and fixed to an engine crank case.

Reference will now be made to the accompanying drawings in which—

Fig. 1 is a side elevation of a complete cam box assembly.

Fig. 2 is a cross section taken on the line II—II of Fig. 1.

Fig. 3 is a longitudinal sectional elevation of the cam box.

Fig. 4 is a plan of the cam box and

Fig. 5 is a cross section taken on the line V—V of Fig. 3.

The construction illustrated shows a preferred application to internal combustion engines of the kind wherein two banks of cylinders A are disposed in mutually inclined positions upon a common crank case B.

The space between the two banks of cylinders is utilised for mounting a cam box which consists of a closed casing 1 having a detachable cover 2 and of considerably greater length than height or width. The interior of this cam box embodies a number of transverse webs 3 and the cam shaft

4, the rocker shaft 5 and cam rockers 6 are all assembled within the said cam box before it is operatively positioned between the cylinder blocks.

Below the closed casing 1 and formed integral therewith is a supporting structure which consists of a hollow box-like member 7 with perforated walls and base as shown in Figs. 3 and 5 and whose base rests upon a horizontal joint face 8 formed upon the upper central portion of the engine crank case B. The cam box is adapted to be fixed in this position by means of long bolts 9 which pass completely through the cover 2, casing 1 and supporting structure 7 and engage sockets formed in the upper portion of the crank case.

The cam shaft 4 is formed with bosses 10 supported in bearings constituted by apertures in the webs 3 which also support bearings 11 for the rocker shaft 5. The webs 3 are also formed with apertures 12 (see Fig. 4) through which pass the bolts 9.

The cam box cover 2 is secured in position by means of nuts and bolts 13 which engage sockets 14 formed in the casing 1 (see Fig. 4), a fluid tight joint being formed between the joint faces of the cover and casing by interposing packing material 15 between them. The cover 2 is also provided with apertures 16 through which pass push rods 17 whose function is to transmit the movements of the cam rockers 6 to the valve rockers in the cylinder heads.

The cam shaft 4 is provided at one end with a pinion 18 through which the drive is transmitted from gearing operated by the crank shaft, the said pinion 18 being housed in a casing 19 bolted at 20 to the end of casing 1 and cover 2 and having its lower portion connected to an end cover of the crank case. The opposite end of the cam shaft carries a bevel gear 21 through which a governor mechanism is driven, this mechanism being supported upon a casing 23 which encloses the bevel gearing and is bolted at 24 to the adjacent end of the casing 1. The cam box cover 2 is also formed with seating surfaces 23 (Fig. 3) on which fuel pumps 26 are adapted to be supported, these pumps being secured in position by means of bolts 27 engaging sockets 28 in the cover 2.

Owing to its length the cam box is conveniently formed in two parts bolted together at 29 as shown in Figs. 3 and 4. The mid portion of the cam shaft carries a gear wheel 30 situated immediately beneath an aperture 31 in the cover 2 through which projects a driven gear 35 engaging the gear wheel 30, the said driven gear being

mounted on a shaft 36 which operates the fuel pumps 26 and being housed within a casing 32 mounted upon a joint face 33 and secured in position thereon by bolts 34. By mounting the governor, and the fuel pumps and their driving gear on the cam box cover in the manner described, the necessity for forming special mountings for these components on other parts of the engine housing or crank case is avoided.

The cam shaft rotates in lubricant contained in the base of casing 1 which is supplied from lubricators 37 mounted on the two end bearings of the rocker shaft and connected to the engine lubricating system. The rocker shaft is hollow and is in communication with the lubricators 37, the rocker shaft having ports at intervals in its length which communicate with ports 38 through which lubricant is conducted to the bearings 11 and passages 39 whereby the cam shaft bearings are lubricated.

In the particular arrangement described and illustrated the rocker shaft is constructed in two separate sections divided by the aperture 31. The cam shaft is also formed in two sections united by bolts 40 which fix the gear wheel 30 in position around two flanges on the adjacent ends of the cam shaft sections.

The arrangement above described possesses numerous advantages all of which assist in expediting and simplifying assembly. For example, the entire cam box assembly with its superimposed engine components can be completed as an independent entity and simply lowered into operative position between the banks of cylinders A. In the detailed assembly, the bearings for the cam shaft and seatings for the rocker shaft bearings are formed by straight line boring or equivalent operations through the transverse webs 3 of the cam box and no skilled alignment of bearings is necessary but only the mounting and fixing of bushings for the rocker shaft bearings.

Although the invention has been particularly described in connection with an engine of the V-type which may be constructed according to our concurrent application No. 9779/42 and provided with a crank case according to our concurrent application No. 9780/42, the invention is not limited to such application but can be adapted to engines of the straight line type.

I claim:

1. A cam shaft mounting for an internal combustion engine having a crank case and two mutually inclined banks of cylinders mounted thereon, comprising an elongated cam box having a flat base for mounting on the top of the engine crank case between the banks of cylinders, and having a separately formed cover on its top, portions of the top of the box sloping downwardly and laterally from the sides of the cover and provided with series of longitudinally spaced perforations, a cam shaft mounted in the lower portion of the cam box, a rocker shaft mounted in the upper portion of the cam box, and rockers mounted on the rocker shaft and extending downwardly and laterally therefrom to opposite sides of the cam shaft, the inner portions of the rockers cooperating with the respective sides of the cam shaft, and the outer portions of the rockers having sockets therein below the respective perforations in the sloping top portions of the box to receive and actuate valve push rods.

2. In an internal combustion engine having a crank case, an elongated cam box formed as a

component separate from the engine, a cam shaft and a rocker shaft mounted in and extending throughout the length of the cam box, a cover for the cam box formed separately therefrom for mounting thereon and having means for supporting an engine accessory on the top thereof, means for securing the cover to the cam box and for securing said accessory on the top of the cover for placing of the complete assembly of cam box, cover and accessory as a unit in position on the crank case, and means for securing said assembly in place on the crank case.

3. In an internal combustion engine as defined in claim 2, including a gear on said cam shaft, and a gear carried by said cover and operatively engageable with said gear on the cam shaft when said cover is mounted on said cam box for driving said accessory.

4. In an internal combustion engine having a crank case and two mutually inclined banks of cylinders mounted thereon and having valves and sets of valve push rods divergently inclined relatively to the crank case, a cam box formed as a component separate from the engine and having a surface thereon formed to seat on the crank case between the banks of cylinders, relatively superposed cam and rocker shafts mounted within the cam box and extending longitudinally throughout the length thereof, and sets of rockers pivotally mounted on the rocker shaft and diverging laterally therefrom and engaging the respective sets of push rods, the intermediate portions of the sets of rockers engaging the respective sides of the cam shaft for actuation thereby.

5. In an internal combustion engine as defined in claim 4, wherein said rocker shaft is mounted in superposed position above said cam shaft, and the upper ends of said rockers are mounted on said rocker shaft and the lower ends of said rockers engage the lower ends of said push rods and are movable in oppositely inclined directions to operate said respective sets of push rods.

6. In an internal combustion engine as defined in claim 4, wherein said cam box is formed internally at intervals in its length with transverse webs provided with sets of lower and upper longitudinally aligned bearings in which said cam shaft and said rocker shaft respectively are mounted.

EDWARD PHILIP PAXMAN.
